UNITED STATES PATENT OFFICE

2,403,992

HAIR CURLER

Allan A. Norin, Chicago, Ill., assignor to Gaylord Products, Incorporated, Chicago, Ill., a corporation of Delaware

Application November 24, 1944, Serial No. 564,926

1 Claim. (Cl. 132—33)

1

This invention relates to hair curlers and is more particularly concerned with the type of hair curler in which a tubular body portion having a thin wall section is slotted to form diametrically opposed fingers to receive a lock of hair to be curled.

This invention further contemplates the provision of a hair curler having a thin walled tubular body portion to receive a bobby pin for retaining a curl in position thereon, after which the curler may be displaced axially from the curl which will then be secured by means of the bobby pin.

It is an object of this invention to provide a hair curler with improved means coacting with the inner walls of the fingers for securing the end of a lock of hair to be curled.

It is a further object of this invention to provide a hair curler which may be inexpensively formed of thermoplastic material, or the like, and which will not readily get out of order.

This invention embodies other novel features, details of construction and arrangement of parts which are hereinafter set forth in the specification and claim, and illustrated in the accompanying drawing wherein:

Fig. 1 is a side elevational view showing a hair curler embodying features of this invention.

Fig. 2 is a longitudinal sectional view of same.

Fig. 3 is a transverse sectional view taken along the line 3—3 of Fig. 2.

Fig. 4 is a transverse sectional view taken along the line 4—4 of Fig. 2.

Referring now to the drawing for a better understanding of this invention, the hair curler is shown as comprising a tubular body portion 6 formed with a relatively thin wall section and having a pair of diametrically opposed slots 7 extending inwardly from one end thereof to provide a pair of fingers 8 and 9. The other end of the body portion is provided with a frusto-conical knob 10 which is preferably knurled to provide a roughened finger gripping portion for rotating the curler. A rib 11 is formed within the tubular body portion 6 and is preferably disposed at right angles to the slots 7. The rib 11 is joined to the finger 9 and provided with a hair clamping edge 12 disposed adjacent the inner wall of the finger 8 and defining therewith an inwardly converging recess 13. The outer ends of the fingers 8 and 9 are rounded at 14 and 15, respectively, to facilitate the insertion of hair into the slots 7. The

2

outer end of the rib 11 is also rounded at its outer end at 16.

This type of hair curler is preferably formed of thermoplastic material to permit flexing movement of the finger 8 toward the edge 12 of the rib 16 for the purpose of locking the hair to be curled therebetween.

In the operation of the curler shown and described, the end of the hair to be curled is inserted between the fingers 8 and 9 for locking engagement in the recess 13 provided between the edge 12 of the rib 16 and the inner wall of the finger 8. By pressing the ends of the fingers 8 and 9 toward each other, the hair is clamped between the edge 12 of the rib and the inner wall of the finger 8. After two or three revolutions of the curler, the pressure may be removed from the ends of fingers 8 and 9 to permit same to assume their normal positions, and the curling operation then continued by merely turning the knob 10. After a curl has been thus formed, a bobby pin is opened to engage the inner wall of one of the fingers and the outside of the curl, after which the curler is withdrawn axially from the curl which is held securely by the bobby pin mounted thereon.

While this invention has been shown in but one form, it is obvious to those skilled in the art that it is not so limited but is susceptible of various changes and modifications without departing from the spirit and scope of the claimed invention.

I claim as my invention:

A hair curler formed of thermoplastic material, comprising a tubular body having a thin wall section, said body having diametrically opposed slots extending inwardly from one end thereof to provide a pair of opposing fingers, the ends of said fingers being rounded to define a flaring mouth opening into said opposed slots, and a rib formed on the inner wall of one of said fingers and centrally disposed within said body, the edge of said rib being disposed in spaced annular relation to the inner wall of the opposing finger to define therewith an inwardly converging hair engaging recess, said rib extending inwardly from the end of its supporting finger and having a rounded end formed to define with the rounded end of the opposing finger a flaring mouth opening into said hair engaging recess.

ALLAN A. NORIN.
